UNITED STATES PATENT OFFICE.

WALTER C. REED, OF BEAVER, PENNSYLVANIA, ASSIGNOR OF ONE-HALF TO JACOB S. STAUFFER, OF BEAVER, PENNSYLVANIA.

WRENCH.

No. 903,002.

Specification of Letters Patent.

Patented Nov. 3, 1908.

Application filed July 7, 1908. Serial No. 442,331.

To all whom it may concern:

Be it known that I, WALTER C. REED, a citizen of the United States of America, residing at Beaver, in the county of Beaver 5 and State of Pennsylvania, have invented certain new and useful Improvements in Wrenches, of which the following is a specification, reference being had therein to the accompanying drawing.

10 This invention relates to wrenches, and the objects of my invention are, first, to provide a quick acting wrench that can be easily and quickly adjusted; second, to provide a strong, durable and inexpensive wrench that 15 can be quickly adjusted to engage an object and then minutely adjusted to obtain a positive grip thereon, and threaded to provide a wrench having a gripping bar that can be renewed.

20 I attain the above objects by a structure that will be presently described and then specifically claimed.

Referring to the drawings: Figure 1 is an elevation of a wrench constructed in accordance with my invention, the wrench being partly broken away, Fig. 2 is a similar view, partly broken away and partly in section, and Fig. 3 is a horizontal sectional view taken on the line x—x of Fig. 1.

30 In the accompanying drawings, 1 designates a shank having a fixed jaw 2. The shank 1 is provided with a longitudinal recess 3 for a gripping bar or rack 4 having teeth 5, said bar or rack being detachably mounted 35 in the recess 3 by rivets 6. Slidably mounted upon the shank 1 is an adjustable jaw 7 having straps 8 and 9 embracing the shank 1, said straps being joined by connecting bars 10.

40 The strap 9 and one of the vertical connecting bars 10 are cut away as at 11 to provide a socket having rounded walls, and arranged within said socket is the upper end of a lever 12, said upper end being rounded so 45 as to conform to the shape of the socket. The said rounded upper end of the lever 12 is pivotally connected in the socket through the medium of a pin 13. The lever 12 at a point removed from its pivoted end is cut 50 away or otherwise provided with an opening 14 in which is mounted a worm nut 16 adapted to engage the teeth 5 of the bar or rack 4. The worm nut 16 is rotatably connected to

the lever 12 through the medium of a longitudinal pin 15 which extends through the 55 worm nut 16 and engages in the upper end of the lever 12.

Secured to the inner side of the strap 8 by screws 17 or similar fastening means is a spring 18 adapted to engage the shank 1 and 60 normally hold the jaw 7 upon said shank, preventing said jaw from sliding except when manually moved.

With the lever 12 in the position illustrated in Fig. 2 of the drawings, the adjustable jaw 65 7 can be easily moved into engagement with a nut or similar object, and the lever 12 swung into parallel alignment with the shank 1. When in this position the worm nut 16 engages the teeth 5 of the bar 4 and retains 70 the jaw 7 in engagement with the object, but in order to obtain a positive grip or to place the jaw 7 in positive engagement with the object, the worm nut 16 is rotated, while the lever 12 is held in engagement with the shank 75 1. When the worm nut 16 is rotated in the proper direction, the adjustable jaw 7 will be further advanced towards the fixed jaw 2, consequently the object will be firmly gripped.

80 The shank 1 and the lever 12 can be made of a sufficient length to permit of a sufficient leverage to be obtained by the wrench.

The wrench in its entirety is made of strong and durable metal, and while in the 85 drawings forming a part of this application there is illustrated the preferred embodiments of my invention, I desire it to be understood that the elements therein can be varied or changed without departing from 90 the spirit of the invention.

Having now described my invention what I claim as new, is:—

A wrench comprising a shank having a fixed jaw on the outer end thereof, said shank 95 provided intermediate its ends with a longitudinally extending recess, a rack bar seated and secured in said recess, a movable jaw having a longitudinally extending opening to receive said shank, a spring secured to one 100 wall of said opening and having a curved free end bearing against the rear face of the shank, said movable jaw provided at one corner with a socket having a curved wall, an elongated lever having a rounded upper end, 105 means for pivoting the upper end of said

lever in said recess, said lever provided adjacent its pivoted end with an opening, a worm mounted in said opening and adapted to engage said rack bar, and a longitudinally extending pin secured in said lever and extending through the worm for rotatably connecting it to the lever.

In testimony whereof I affix my signature in the presence of two witnesses.

WALTER C. REED.
